UNITED STATES PATENT OFFICE.

JOHANNES PIERITZ, OF SIEVERTSHAGEN, GERMANY.

OAR.

973,067.

Specification of Letters Patent. Patented Oct. 18, 1910.

Application filed August 2, 1909. Serial No. 510,934.

To all whom it may concern:

Be it known that I, JOHANNES PIERITZ, a subject of the King of Prussia, German Emperor, resident of Sievertshagen, Germany, have invented certain new and useful Improvements in Oars, of which the following is a specification.

This invention relates to oars of the type where the oarsman can look toward the head 10 of the boat instead of turning his back in the direction of movement as is the case with the oars used at present.

In the accompanying drawings the improved oar is shown by way of example.

Figure 1 is a perspective side view of an improved oar. Fig. 2 represents in ground plan the toothed gear and Fig. 3 shows the case in side view in which the toothed gear is inclosed.

The improved oar consists of the blade *a*, the casing or box *b* and the handle *c*. The parts *a* and *c* are pivoted with their inner and outer forkshaped ends respectively on square pivots *d* and *d*¹ which are fixed each 20 upon the axle of a horizontal toothed wheel *e* and *e*¹ respectively. The oar is mounted adjustably in a vertical bracket which is

fixed upon the rim of the boat. If the handle *c* is pulled its toothed wheel *e*¹ which meshes with the toothed wheel *e* revolves the same in opposite direction, that is to say, the blade *a* is pushed back and the boat is moved forward.

I claim:

An improved bowfacing oar, comprising 35 in combination, a handle part, a blade part and a box pivotably mounted upon the gunwale of the boat, square bolts projecting through the topplate of said box, two toothed wheels meshing the one with the other and 40 located in said box, the vertical axles of said toothed wheels carrying said square bolts, a forkshaped outer end of the handle part mounted upon the inner square bolt and a forkshaped inner end of the blade part 45 mounted upon the outer square bolt, substantially as described and shown, and for the purpose set forth.

In witness whereof I have hereunto set my hand in the presence of two witnesses.

JOHANNES PIERITZ.
